AIRPLANE FABRIC ATTACHMENT

Karl Schmidt, United States Navy

Application June 3, 1938, Serial No. 211,596

1 Claim. (Cl. 244—132)

(Granted under the act of March 3, 1883, as amended April 30, 1928; 370 O. G. 757)

The present invention relates to airplane fabric attachments and it has a particular relation to the cap-strips of the wing structure to which the fabric is secured.

5 One of the objects of the present invention is the provision of a rib cap-strip which is so constructed that the fabric may be secured thereto throughout its entire length and which will provide a smooth flush surface which is highly desirable in high speed airplanes.

10 Another object of the invention is the provision of a fastening means for aircraft fabric in which the full strength of the fabric is developed when abnormal air-loads are imposed thereon.

15 With these and other objects in view, as well as other advantages that may be incident to the use of the improvements, the invention consists in the parts and combinations thereof hereinafter set forth and claimed, with the understanding 20 that the several necessary elements constituting the same may be varied in proportion and arrangement without departing from the nature and scope of the invention, as defined in the appended claim.

25 In order to make the invention more clearly understood, there is shown in the accompanying drawing, means for carrying the invention into practical use, without limiting the improvements in their useful application to the particular construction, which, for the purpose of explanation, have been the subject of illustration.

In the accompanying drawing:

Fig. 1 is a transverse sectional view through a cap-strip and fabric attaching means constructed 35 in accordance with the invention; and

Fig. 2 is a fragmentary side elevational view on a reduced scale of the cap-strip structure shown in Fig. 1.

Referring to the drawing, a cap-strip of an airplane rib structure is shown as comprising two 40 complementary angle strips 10, the vertical flanges 11 of which are secured together by rivets 12 and offset at 13 to provide a space 14 and the horizontal flanges 15 of which extend in opposite 45 directions to provide a supporting surface for the load fabric 16. When the fabric is secured to the cap-strip it is tucked down into the space 14 by means of a load-strip 17 having a rounded lower edge which is forced into the space along with the 50 fabric and secured in position by means of keeper-pins 18 provided with heads 19. These pins extend horizontally through the flanges 11 of the cap-strip, reinforcing angle members 20, the fabric 16 and the load-strip 17 and are formed with

pointed extremities 21 to pierce the fabric between the threads without unduly rupturing the same. The pins 18 are themselves maintained against displacement by washers 22 and a single locking wire 23 which is threaded through holes 5 in a series of pins adjacent to the washers and which preferably extends the full length of the cap-strip. A length of tape 24 is cemented to the fabric covering over the depression formed where the fabric is tucked into the space 14 so 10 as to provide a smooth flush surface.

It will be apparent from the foregoing that the entire lift load in the plane of the rib is transmitted to the spaced keeper-pins by means of the load-strip 17 which functions as a continuous 15 beam; that the lift load exerts a shearing reaction on the keeper-pins instead of placing them under tension, as in former structures; that the flanges of the cap-strip are relatively wide to resist bending action and consequent separation of 20 the two halves of the cap-strip between the keeper-pins; and that there is no necessity of having the keeper-pins fit tightly as they are always under shear loading.

It will be understood that the above description 25 and accompanying drawing comprehend only the general and preferred embodiment of the invention, and that various other changes in the construction, proportion, and arrangement of the parts may be made by those skilled in the art 30 without departing from the nature and scope of the invention as defined in the appended claim.

The invention described herein may be manufactured and/or used by or for the Government of the United States of America for governmental 35 purposes without the payment of any royalties thereon or therefor.

Having described my invention, I claim:

Attachment for aircraft fabric covering comprising a cap-strip formed of two complementary 40 angle members secured together and having a space therebetween into which the fabric extends, a load-strip disposed within said space and over the fabric therein, the outer edge of said load-strip being disposed within the plane of said covering to provide a smooth unbroken surface, and fastening pins extending transversely through said cap-strip, fabric and load-strip and disposed parallel to the plane of said covering for securing the fabric and load-strip in said space, said 45 pins being thus subjected to shearing strains only when the covering is air-loaded.

KARL SCHMIDT.
